UNITED STATES PATENT OFFICE.

DAGOBERT CURTI, OF AMSTERDAM, NEW YORK, ASSIGNOR TO STEPHEN SANFORD, OF SAME PLACE.

DESIGN FOR CARPETING.

Specification forming part of Design No. 11,377, dated August 26, 1879; application filed August 4, 1879.
[Term of patent 3½ years.]

To all whom it may concern:

Be it known that I, D. CURTI, of Amsterdam, Montgomery county, State of New York, have invented or produced a new and original Design for a Pattern to be Inwrought into In-grain and other Carpeting; and I do hereby declare that the photograph accompanying this specification does give and convey to any one skilled in the art of carpet-weaving a defined and thorough description of the nature of my invention, and is sufficient to enable any one skilled in the art of carpet-weaving to use my invention.

What I claim as my invention, and desire to secure by Letters Patent, is—

The design for carpeting, as shown in the photograph accompanying this specification.
